MUFFLER-FILTER APPARATUS FOR AIR FLOW PASSAGES

Alfred Weiland, Philadelphia, Pa., assignor to Baldwin-Southwark Corporation, a corporation of Delaware

Application September 16, 1935, Serial No. 40,800

8 Claims. (Cl. 181—56)

This invention relates generally to a combined noise silencing and filter apparatus for air flow passages particularly in a self-contained air conditioning unit.

5 In air conditioning apparatus, especially of the self-contained room unit type having a compressor, condenser, evaporator and blower for circulating room air over the evaporator, there is likely to be some noise caused by the blower or compressor mechanism or by the flow of air through the passages and over the fins of the evaporator. It is particularly desirable to maintain all noise at a minimum inasmuch as such a self-contained unit is placed directly within the 10 room occupied by a person.

It is one object of my invention to provide for the room air inlet and discharge of an air conditioning unit an improved muffler and filter system and apparatus that is economical in manufacture and maintenance, is efficient both in 15 filtering and in silencing noise while at the same time offering minimum resistance to the air flow, is compact and pleasing in appearance and can be readily removed for cleaning or inspection. A further object is to provide an improved filter-muffler adapted to effectively direct and distribute air into the room and into the inlet of the blower.

Other objects and advantages will be more apparent to those skilled in the art from the following description of the accompanying drawings 20 in which:

Fig. 1 is a perspective of a self-contained air conditioning unit embodying my improved muffler system, parts thereof being broken away to show details of construction;

35 Fig. 2 is a plan view of the discharge muffler with the inflowing baffles omitted for sake of clarity;

Fig. 3 is a transverse section on the line 3—3 of Fig. 2;

40 Fig. 4 is a vertical fragmentary section on the line 4—4 of Fig. 1;

Figs. 5, 6, 7 and 8 are rear views of modified intake filter-mufflers.

45 In the particular embodiments of the invention which are shown herein merely for the purpose of illustrating certain specific forms among possible others that the invention might take, I have shown in Fig. 1 an air conditioning unit generally indicated at 1 of any suitable type, although specifically of the form shown in application of H. L. Galson, Serial No. 648,772, filed December 24, 1932. The specific construction of such a unit does not constitute a part of my present 50 invention. Hence it will suffice to state that the

unit contains a compressor, an air cooled condenser, an evaporator, and blowers, one for circulating room air over the evaporator and another for circulating outside air over the condenser, although it will be apparent that my improved muffling and filtering system is applicable to remote cooling units having only a cooling element without the compressor or condenser, as well as being applicable to the inlet and discharge openings for various types of passages. However, the invention is particularly applicable to the unit herein disclosed as it has in one end a room air inlet 2 communicating with a blower 3 and an evaporator passage which terminates in a horizontal outlet 4. This outlet lies in the top surface of the mechanical structure of the unit and is specifically of elongated form, Fig. 2, located forwardly of the unit but does not extend for its full length. A cabinet 5 entirely encloses the mechanical construction of the unit and is provided with a large rectangular opening 6 in one end to receive the inlet muffler generally indicated at 7. 5 10 15

The inlet muffler comprises a relatively large rectangular frame having an end panel 8 and side pieces 9 extending entirely around the panel edges, this relatively shallow box-like construction being open on its inner side. Disposed near the top of the panel is a series of preferably vertically elongated openings 10 between which, on the inside of the box, are a series of vertically extending short baffles 11 and a pair of substantially centrally located long baffles 12 all equally spaced in parallel relation and at right angle to the panel. The foregoing baffles are covered with any suitable sound absorbing material such as shown in application of mine, Serial No. 36,502, filed August 16, 1935, such material also functioning as an impact filter. All of the baffles extend from the inner face of front panel 8 to the plane of the outer edge of side pieces 9. 25 30 35

On the discharge side of the unit, the cabinet is provided, Fig. 1, with a top portion 14 and a raised outlet portion 15 at the rear of the cabinet, extending for the full length of the unit in vertically spaced relation to the top of passage 4. Disposed within and extending for the full length of the raised outlet 15 is an upper series of longitudinally extending and slightly forwardly inclined baffles 16 while a lower series of 40 45 50

rearwardly inclined longitudinal baffles 17 are placed with their upper edges substantially adjacent the lower edges of the upper baffles 16, thereby forming substantially parallel V-shaped air flow passages. The lower edge of the series 55

of baffles 17 is substantially in the plane of top 14 whereby air discharged from evaporator passage 4 first flows, as indicated by arrow line 18, Fig. 1, into the common chamber 19 and thence 5 rearwardly therein to baffles 16 and 17 which direct the air forwardly into the room. To insure uniform distribution of air in chamber 14 and outlet 15, there is provided a vertically extending but angularly disposed baffle 20 within 10 chamber 19. This baffle overlies evaporator outlet 4 about midway of its length and extends vertically from beneath top 14 down to the inner top surface 21 of the unit in which outlet 4 terminates, thereby compelling air from the two 15 divided portions of outlet 4 to be equally distributed throughout the length of the elongated outlet 15.

In the operation of the apparatus, room air flows inwardly through the series of openings 20 10 and thence downwardly through the parallel passages formed between the series of vertical baffles 11 and 12. The air upon leaving the end of baffles 11 turns laterally inwardly to fan inlet 2 while the air flowing downwardly between baffles 25 12 turns directly into the inlet. The baffles 11 are shorter than baffles 12 due to the necessity of the air turning laterally from baffles 11 into the blower inlet 2, but baffles 12 insure symmetrical flow of air into inlet 2. The air thence 30 flows upwardly through the evaporator passage 4 and is turned rearwardly as indicated by line 18, Fig. 1, and is longitudinally distributed by angular baffle 20, Fig. 2, and then flows upwardly first through the lower rearwardly inclined baffles 17 and then forwardly through upper baffles 16, Fig. 1. Due to all of the foregoing inlet and discharge baffles being covered with silencing material preferably of the type disclosed in said previously mentioned application of mine, it is 40 seen that the air travels over a very large area of muffler surface with a uniform and continuous flow through such baffle passages. It has been found that such an arrangement efficiently muffles any noise and filters the air while at 45 the same time permitting efficient air flow through the unit.

It will, of course, be understood that various modified arrangements of the baffles may be employed while retaining the broad principles as 50 herein disclosed, and certain of these arrangements are shown in Figs. 5 to 8. In Fig. 5, a series of staggered baffles 25 are provided within the box 7. Instead of having a series of openings 10 as shown in Figs. 1 and 4, a single elongated opening 26 is provided and also the lower ends of baffles 25 preferably terminate short of the blower inlet whose position is diagrammatically indicated by a dotted circle 24. In Fig. 6, a series of zig-zag baffles 27 are provided 55 between the inlet 28 and blower while a pair of angular baffles 29 are provided in the lowermost corners of the box 7. In Fig. 7, a longer air flow passage is provided in box 7 by having the room air inlet in the lower edge as indicated at 60 30 from which the air flows upwardly along the outside of angular baffles 31 disposed substantially tangent to the periphery of inlet 2 and thence around the upper ends of said baffles 31 and down through a series of vertical baffles 32. As 65 shown in Fig. 8, the angular baffles 31 may be provided with a series of lateral openings 33.

From the foregoing disclosures it is seen that I have provided a flow muffling system having flow directing and distributing features and which is not only pleasing in appearance but is

relatively simple and economical in manufacture, maintenance and operation and which has the further function of operating as an impact filter whereby the long travel of air over the muffler surfaces will permit dirt to adhere to 5 such surfaces and thus filter the air.

It will of course be understood that various changes in details of construction and arrangement of parts may be made by those skilled in the art without departing from the spirit of the 10 invention as set forth in the appended claims.

I claim:

1. A muffling system for an outlet of an air flow passageway comprising, in combination, 15 means forming a chamber into which the air initially flows from said outlet, and means forming outlet baffle passages of substantially V-shaped formation communicating with said chamber to discharge the air in a predetermined direction.

2. A muffling system for the inlet and outlet of 20 an air flow passage comprising, an elongated baffle chamber one end of which communicates with the inlet of said passage and the other end of which has air admission openings, a series of substantially straight baffles forming elongated 25 passages extending from said admission openings to said passage inlet, means forming a chamber over the outlet of said passage, and means forming a series of baffle passages communicating with said chamber so as to freely discharge air therefrom in a predetermined direction.

3. A muffling system for an air flow passage having an outlet, means forming a chamber disposed over and also extending laterally of said outlet including an upper wall immediately over 35 said outlet in spaced relation thereto, and a plurality of silencing baffle passages located above and communicating with said laterally extending portion of said chamber, whereby the air flows upwardly through said outlet into said 40 chamber at a point beneath said upper wall and then laterally and thence upwardly through said baffle passages to be discharged therefrom in a given direction as determined by said baffles.

4. The combination set forth in claim 3 further characterized in that said chamber extends laterally from said outlet in two directions while said baffle passages communicate with said chamber in only one of said laterally disposed portions thereof.

5. A muffling system for an air flow passage in an air conditioning unit having an outlet in the top thereof but of shorter length and width than that of the unit, means forming a horizontal chamber extending for the full length and width of the unit and having a portion overlying said outlet, and means forming a plurality of silencing baffle passages along one longitudinal side 55 of said chamber and adapted to discharge the air forwardly toward the other longitudinal side 60 of the unit.

6. The combination set forth in claim 5 further characterized by the provision of an angular baffle overlying the outlet of said passage for distributing the air to longitudinally spaced portions of said baffle passages.

7. A muffling system for the inlet passage of an air flow passage comprising means forming an elongated chamber one end of which overlies and is wider than said inlet and the other end of which is provided with air admission openings, a plurality of silencing baffles disposed within said chamber and extending in the direction of elongation thereof, certain of said baffles being of sufficient length to extend directly over 70 75

said inlet and other of said baffles being of shorter length adjacent said inlet, whereby the elongated baffles cause air to flow directly to said inlet while the shorter baffles permit air to turn laterally from their shortened ends into said inlet.

8. A muffling system for the inlet of an air flow passage extending through an air conditioning unit comprising, in combination, a cabinet

enclosing said unit and having an opening therein adjacent the inlet of said air flow passage, means forming a chamber removably disposed in said opening, means forming a series of silencing baffle passages within said chamber, and means providing an air admission opening in said chamber forming means.

ALFRED WEILAND.
